UNITED STATES PATENT OFFICE.

GUSTAV STRUCK, OF HAMBURG, GERMANY.

DEVICE FOR EVAPORATING WATER IN HEATING APPARATUS FOR HEATING BUILDINGS AND THE LIKE.

No. 894,077.

Specification of Letters Patent.

Patented July 21, 1908.

Application filed August 16, 1907. Serial No. 388,832.

To all whom it may concern:

Be it known that I, GUSTAV STRUCK, a subject of the German Emperor, and resident of No. 49 Klosterallee, Hamburg, Germany, 5 have invented certain new and useful Improvements in Devices for Evaporating Water in Heating Apparatus for Heating Buildings and the Like, of which the following is a specification.

10 The present invention has for its object a device for evaporating water in hot-water or heating apparatus especially of the kind which are employed in dwellings, offices and the like.

15 The novelty consists in a box which is filled with water and arranged underneath the existing heating apparatus and partly encircling the heating tube in such a manner that the latter transmits its heat to the water.

20 The accompanying drawing represents two forms of construction of the invention.

Figure 1 shows how the box is arranged within the foot of the heating apparatus. Fig. 2 shows, perspectively, the novel way 25 the box is hung underneath the heating apparatus.

In the first form of construction (Fig. 1) the box *a* is held against the lower horizontally arranged tube *d* by bent bars *b* which, at 30 the same time serve as feet to the former. The said box is provided with guidings *c* in such a manner that the box can be guided and held fast on the said bars and against the heating body by screw-nuts *c¹*. The top 35 ends of the side walls of the said box are cut out to suit the shape and size of the said tube

and provided with packing material in such a way, that, on the box being pressed against the tube, the box is made water-tight at the lower sides thereof while at the top sides rubber plates *e* or the like are movably arranged at the point *f* and are held thereon by the neighboring walls of the boxes which are provided with springs *h* for the purpose.

In the form of construction shown in Fig. 45 2, the box is hung underneath the heating body and made water-tight by rubber plates *k* which are made to suit the shape of the tube *d*, inserted in grooves on the box and tightened by screws *s*. Instead of this arrangement, the feet of the heating apparatus, can be placed in the water box, or the feet omitted from the apparatus. In this latter case no packing need to be employed.

I claim:

55 In a device for evaporating water in heating apparatus the combination of a heating apparatus, a box the side-walls of which have grooves arranged underneath this heating apparatus and partly encircling the heating tube, bent bars guided in guidings of the said box adapted to press the said box against the said heating tube, rubber plates movably arranged in the box adapted to make the latter water-tight, springs adapted 60 to press said rubber plates against the sidewalls of the box, substantially as shown and described.

GUSTAV STRUCK.
